UNITED STATES PATENT OFFICE.

JOHN G. SCHMIDT, OF MILWAUKEE, WISCONSIN.

COMBINED SPRAY AND PAINTBRUSH.

Application filed April 10, 1922. Serial No. 551,183.

To all whom it may concern:

Be it known that I, JOHN G. SCHMIDT, a citizen of the United States, and a resident of Milwaukee, in the county of Milwaukee, and State of Wisconsin, have invented a new and useful Improvement in Combined Spray and Paintbrushes, of which the following is a full, clear, and exact description.

My invention relates to improvements in combined spray and paint brushes, and it consists in the combinations, constructions, and arrangements herein described and claimed.

An object of my invention is to provide a combined spray and paint brush which has the advantages of the spray and of the ordinary paint brush without the disadvantages of either.

A further object of my invention is to provide a device of the character described in which a plurality of nozzles are used for applying the spray, whereby a more even coat of paint is effected.

A further object of my invention is to provide a device of the character described in which the spray is adjustable with respect to the paint brushes.

A further object of my invention is to provide a device of the character described in which the parts are readily assembled for use or disassembled for cleaning.

A further object of my invention is to provide a device of the character described which is simple in construction, and is durable and efficient for the purpose intended.

Other objects and advantages will appear in the following specification, and the novel features of the invention will be particularly pointed out in the appended claims.

My invention is illustrated in the accompanying drawings, forming part of this application, in which—

Figure 1 is a side elevation of the device,

Figure 2 is a plan view of the device, and

Figure 3 is a longitudinal section of the spray.

In carrying out my invention, I provide a spray brush 1 which has an inner paint or other liquid receiving reservoir 2, and an annular compressed air chamber 3 (see Figures 1 and 3). The chamber 3 is disposed concentrically around the chamber 2 and is provided with an inlet 4. The chamber or reservoir 2 is provided with an inlet 5. The chamber 2 has a plurality of outlet openings 6 which are alined with respect to each

other and which are disposed on the opposite side to which the inlets 4 and 5 are disposed. Nipples 7 of the shape shown in Figure 3 are disposed in the openings 6 and project through threaded openings 8 in the outer wall of the chamber 3. It is obvious that there are as many openings 8 as there are openings 6, and that each opening 6 carries a nipple 7. The outer wall 9 of the member 1 carries nozzles 10. These nozzles have threaded shanks 11 which are disposed in the openings 8, whereby the nozzles are securely locked in place. The bore of the nozzles 10 are tapered and receive the ends of the nipples 6. If desired, the bores 12 of the nozzles 10 may be reduced so as to bear against the outer end of the nipples 6. In this case, the portion of the nozzle 10 which bears against the nipple 6 would be provided with grooves through which the compressed air from the chamber 3 is passed. The bore of the nipples 6 is alined with the exit opening 13 of the nozzles 10 so that paint or any other liquid in the container 2 may pass through the nipples 6 and out through the openings 13.

The outlets 4 and 5 are disposed in an annular projection 14 which is integral with the member 1. A hollow handle 15 is disposed over the projection 14 and has its sides 16 extended so as to enclose the sides of the member 1 (see Figure 1). The handle 15 encloses the pipes 17 and 18 which are disposed in the inlet openings 4 and 5. The pipes 17 and 18 may be threaded, if desired, so as to rigidly secure the pipes to the projection 14. As clearly shown in Figure 2, the pipes 17 and 18 are connected to conduits 19 and 20, these conduits being provided with valves 21 and 22. The conduit 19 is adapted to convey compressed air to the chamber 3 and the conduit 20 is adapted to convey paint or a like liquid to the chamber 2.

A metal saddle 23 is clamped in adjusted position to the handle 15 by means of a nut 24. This saddle has laterally extending arms 25 which are provided with slots 26 therein (see Figure 2). Paint brushes 27 are secured to the arms 25 by means of set screws 28. It is obvious from the foregoing structure that the brushes 27 may be moved toward or away from the spray brush 1. It is also to be noted that the brushes 27 may be swung angularly with respect to each other.

From the foregoing description of the various parts of the device, the operation thereof may be readily understood. The handle 15 is preferably adjusted with respect to the frame 23 so that the nozzles 10 are spaced away from the ends of the brushes 27. In Figure 1 I have shown a dotted line 29 which represents the wall of an object to which the liquid, such as paint or the like, is to be applied. The nozzles 10 do not touch the wall 29 and are preferably spaced the distance from the wall which is shown in Figure 1.

In applying a liquid, such as paint or calcimine, to the wall 29, the valves 21 and 22 are opened to the required distance so as to permit the required pressure to be applied to the compressed air and to the liquid. The liquid will flow out through the nipples 6 and into the openings 13 where it will come into engagement with the compressed air from the chamber 3. The compressed air will drive the liquid outwardly with sufficient force to make a spray. This spray will contact with the wall to which the device is applied. In the use of ordinary sprays in which paint, varnish, calcimine, or other decorative coating is to be applied to a wall, a slight air current or a draft carries the atomized particles from the point of the intended application, some being entirely carried away and others being dropped on the ground causing a loss of material and sloppy work. With my present device, however, the brushes 27 act as a protective shield and also apply the liquid on the wall in the manner in which the ordinary paint brush applies the liquid to a wall. As the liquid is being sprayed upon the wall, the device is moved so as to cause either of the brushes 27 to engage with the liquid on the wall. It is obvious that the device may be moved as fast as desired, since the liquid will be supplied to the brushes at a constant flow. The nozzles 10 are provided in a row so as to give a more uniform flow to the liquid and over a great area. As heretofore stated, the brushes 27 may be moved toward or away from the nozzles 10, or may be swung angularly with respect to each other. The brushes may be detached and cleaned in the ordinary manner, or new brushes may be substituted for the old ones. As heretofore stated, the device is very simple in construction, and is efficient and durable for the purpose intended. It has the advantages of the paint brush and the spray without the disadvantages of either.

I claim:

1. A device of the character described

comprising a spray nozzle having a handle, a frame adjustably carried by said handle, and brushes carried by said frame, said brushes being disposed on opposite sides 65 of said spray nozzle and being adapted to space said nozzle from a wall.

2. A device of the character described comprising a member having a plurality of spray nozzles therein, said member being 70 provided with a handle, a frame adjustably carried by said handle, a pair of brushes carried by said frame and being disposed on the opposite sides and parallel with the line of spray nozzles, said brushes being 75 adapted to space said nozzles from a wall.

3. A device for applying a liquid coating comprising a hollow handle, a spray nozzle carried thereby, means for delivering a liquid and air to said nozzle through said handle, a frame secured to said handle and adjustable longitudinally thereof, a brush carried by said frame, and means for adjusting the position of the brush toward and away from said nozzle. 80

4. A device of the character described comprising a member having a liquid and air reservoir therein, a line of outlet nozzles communicating with said liquid and air reservoirs, whereby the air in said air reservoir is adapted to spray the liquid from said nozzles, a hollow handle secured to said member, a frame adjustably secured to said handle and having wings, a brush adjustably carried by each wing and being adapted to space the nozzles from a wall, said nozzles lying in a plane parallel with the planes of said brushes. 85

5. A device for applying a liquid coating comprising a hollow handle, a spray nozzle carried thereby, means for delivering a liquid and air to said nozzle through said handle, a frame secured to said handle and adjustable longitudinally thereof, a brush secured to said handle on each side of said nozzle, and means for adjusting each of said brushes toward and away from said nozzle. 100

6. A device for applying a liquid coating comprising a hollow handle, a line of spray 110 nozzles carried thereby, means for delivering a liquid and air to said spray nozzles through said handle, a frame carried by said handle and adjustable along the handle parallel to the axis thereof, brushes carried 115 by said frame on each side of said nozzle, said brushes being parallel with the line of the nozzles, and means for permitting the adjustment of each brush toward or away from the nozzle.

JOHN G. SCHMIDT.
